UNITED STATES PATENT OFFICE.

JOHN L. MONTGOMERY, OF BOSTON, MASSACHUSETTS.

REVERSIBLE SHADE-SUPPORTING BRACKET.

1,321,233.

Specification of Letters Patent.

Patented Nov. 11, 1919.

Application filed February 24, 1919. Serial No. 278,571.

To all whom it may concern:

Be it known that I, JOHN L. MONTGOMERY, a citizen of the United States, residing at Boston, county of Suffolk, and State of Massachusetts, have invented an Improvement in Reversible Shade-Supporting Brackets, of which the following description, in connection with the accompanying drawings, is a specification, like characters on the drawings representing like parts.

This invention relates to a shade fixture or bracket of novel construction as will be described, whereby a single bracket can be used for both sides of the window and can be applied to the inside and outside of the window casing, and when applied to the inside is brought in close proximity thereto as will be described.

The bracket or fixture is provided with a cord separator as will be described.

The particular features of the invention will be pointed out in the claims at the end of this specification.

Figure 1 is an elevation of a sufficient portion of a window provided with an adjustable shade and with supporting brackets embodying the invention.

Fig. 2, a detail showing one of the brackets fastened to the inside of the casing.

Fig. 3, a side elevation of Fig. 2 looking toward the left.

Fig. 4, a plan view of the bracket shown in Fig. 2.

Fig. 5, an elevation of the window with the brackets applied to the outside of the casing.

Fig. 6, a front elevation of the bracket shown in Fig. 5, and

Fig. 7, a side elevation of Fig. 6 looking toward the right.

The bracket herein shown as embodying this invention may be a casting or as is preferred may be of sheet brass or other metal, and consists of a plate or member 10 preferably substantially rectangular in form and provided with a top flange 12, a bottom flange 13 extended in the same direction as the flange 12, a side flange 14 of a width substantially equal to the width of the top and bottom flanges 13, 12, and an opposite side flange 15, which is preferably curved as shown in Fig. 3 and is of a width not greater than the side flange 14. The side flanges 14,

15, extend from the plate 10 in the same direction for a purpose as will be described. 55

The plate 10 is provided with an opening 16 adjacent the side flange 15 and with a flange 17, which may be struck up from the plate to form the opening 16 and which extends in the same direction as the side flange 15, with which it coöperates to form bearings for the shaft 20 of a grooved pulley 21, which is of a diameter less than the width of the side flange 14, so as to leave ample space for the free passage of cords 22, 23, 60 between the pulley and the inside surface 24 of the casing 25 when the bracket is used on the inside of the window casing.

The plate or member 10 may be designated the back plate of the bracket and it is provided with holes for the passage of screws 26, when the back plate is fastened to the casing 25 on the inner side thereof as shown in Figs. 1 to 4. The side flange 14 is provided with similar holes for the passage of screws 27, as represented in Fig. 7, when the bracket is fastened to the window casing on the outside thereof, as represented in Figs. 5 to 7.

The top and bottom flanges 12, 13, are provided with openings 30, 31, in alinement for the passage of guide rods 32, 33, located on opposite sides of the window casing and on which slide the bearing members 34, 35, for the journals 36, 37, of the roller 38 on which 80 the window shade 39 is wound.

Each guide rod is extended through only one flange of the bracket with which it is used, which is the lower flange of either the right or left bracket. 90

As represented in Figs. 1 to 4, the guide rod 32 extends through the opening in the flange 13, and the guide rod 33 extends through the opening in the flange 12, inasmuch as the bracket used on the left side of the window casing is reversed with relation to the bracket used on the right side of said casing, and the top flange 12 of the right hand bracket becomes the bottom flange of the left hand bracket. By extending the guide rods through only the lower flange, they are free to hang vertically and parallel with the window casing. 95

The bearing members 34, 35 for the shade roller 38 may be of any suitable construction, and are preferably of sheet metal and 100

provided with upper and lower ears 40, 41, which embrace the guide rod so as to slide freely thereon.

The lower ends of the guide rods are secured by nuts 42 to brackets or angle plates 43, which are fastened to the window casting in vertical planes through the opening in the bottom flanges of the supporting brackets.

- 10 The bearing members 34, 35 are raised by means of the cords 22, 23, one cord as 22 being herein shown as fastened to the bearing member 35 and passed over the pulley 21 of the left hand bracket, thence 15 across the window over the pulley 21 of the right hand bracket and then extended down to a cleat 45 near the bottom of the window. The other bearing member 34 has fastened to it one end of the cord 23, which is passed 20 over the pulley of the right hand bracket and thence down and between the pulley and a pin 46 supported by the flanges 15, 17, below the pulley, the cord 23 being connected to the cord 22 as at 50.
- 25 By reference to Figs. 1 and 5, it will be seen that a single construction or type of bracket can be used on the inside and outside of the window casing, and for both the right and left hand brackets, and by 30 reference to Figs. 2 to 4, it will be seen that when the brackets are used on the inside, the back plate or member 10 is capable of engaging the inner surface of the casing, so that the guide rods are brought in close 35 proximity to the casing, which not only presents a better appearance but enables the brackets to be firmly secured in position by substantially short screws.
- 40 The bracket may be provided with pins 46 located above and below the pulley 21 or the flanges 15, 17 may be provided with

suitable holes for the insertion of said pins, when the bracket is placed in its operative position.

Claims:

1. A reversible shade supporting bracket, comprising a back plate provided with top and bottom flanges having holes through them, and with a plurality of side flanges extended from said back plate in the same direction as the top and bottom flanges and substantially at right angles to the latter, and a pulley located between two of said side flanges and journaled therein. 45

2. A reversible shade supporting bracket, comprising a back plate provided with screw holes, and having top and bottom flanges extended in the same direction and provided with openings for the passage of a guide rod, a side flange extended from said back plate in the same direction as the top and bottom flanges and substantially at right angles to the latter and provided with screw holes, and additional side flanges extended in the same direction as the top and bottom 60 flanges and substantially at right angles to the latter and forming bearings for the shaft of a pulley located between them. 65

3. A reversible shade supporting bracket, comprising a back plate provided with top and bottom flanges having holes through them, and with a plurality of side flanges extended from said back plate in the same direction as the top and bottom flanges, a pulley located between two of said side 70 flanges and journaled therein, and a cord separating pin carried by said side flanges below said pulley. 75

In testimony whereof, I have signed my name to this specification.

JOHN L. MONTGOMERY.
